UNITED STATES PATENT OFFICE.

WALTER C. MARMON, OF INDIANAPOLIS, INDIANA, ASSIGNOR TO THE NORDYKE & MARMON COMPANY, OF SAME PLACE.

SEPARATING AND BOLTING MACHINE.

SPECIFICATION forming part of Letters Patent No. 655,881, dated August 14, 1900.

Application filed November 3, 1899. Serial No. 735,686. (No model.)

To all whom it may concern:

Be it known that I, WALTER C. MARMON, a citizen of the United States, residing at Indianapolis, in the county of Marion and State 5 of Indiana, have invented certain new and useful Improvements in Separating and Bolting Machines, of which the following is a specification.

My invention relates to that class of sifting and separating machines by which mill products are suitably graded, and especially is an improvement upon or addition to that machine which forms the subject-matter of the application of Allen C. Brantingham, filed 15 July 3, 1899, Serial No. 722,689; and it consists in a means whereby the direction of the material in passing through the machine may be variably controlled, so that upon certain occasions the product may be caused to be 20 discharged in one direction and into a certain selected receptacle or receptacles and at other times may be caused to be discharged in another direction and into another selected receptacle or receptacles.

25 Said invention will be first fully described and the novel features thereof then pointed out in the claims.

Referring to the accompanying drawings, which are made a part hereof and on which 30 similar reference characters indicate similar parts, Figure 1 is an elevation of one side of a section of a machine of the character described as seen from the dotted line 11 along-side Fig. 2. Fig. 2 is a vertical sectional view 35 as seen from the dotted line 22 in Fig. 1; Fig. 3, a view as seen from the dotted line 33 in Fig. 2; Fig. 4, a horizontal sectional view as seen when looking downwardly from the dotted line 44 in Fig. 3; Fig. 5, a horizontal 40 sectional view, on an enlarged scale, as seen from the dotted line 55 in Figs. 1 and 6; Fig. 6, a transverse detail sectional view as seen from the dotted line 66 in Fig. 5; Fig. 7, a detail front elevation illustrating the construction and arrangement of one of the operating-levers and its connection to the bridge-bar and showing also, by means of dotted and full lines, the two positions of the handle end of said lever; Fig. 8, a detail 45 transverse sectional view through the handle end of the lever and the detent which it trav-

els over and with which it engages as seen from the dotted line 88 in Fig. 7; Fig. 9, a transverse sectional view at the central or pivot or fulcrum point of the lever as seen 55 from the dotted line 99; Fig. 10, an underside plan view at the point where the lever engages with the bridge-bar, showing the arrangement of the engaging member; Fig. 11, a detail transverse sectional view as seen 60 from the dotted line 1111 in Fig. 7, showing the said engaging member and the parts to which it is connected; Fig. 12, a perspective view illustrating the shifting-gates and the rods by which they are connected and operated and showing in detail the means whereby the rods are connected to the gates; Fig. 13, a detail vertical sectional view as seen 65 from the dotted line 1313 in Fig. 12; Fig. 14, a horizontal sectional view as seen from the dotted line 1414 in Fig. 12; Fig. 15, a vertical sectional view as seen from the dotted line 1515 in Fig. 12, and Fig. 16 a detail elevation of one of the dovetailed heads which are used in making the engagement between 70 the rods and the gates.

The frame, the sieves, the receptacles, and the general means for operating the machine are by preference the same as those illustrated in the Brantingham application, Serial 80 No. 722,689, above referred to, and are thought to need no special description. I, however, mount upon any desired number of the sieves in said machine shifting-gates by which the open sides of said screens or sieves, through 85 which the treated material is discharged therefrom, may be opened and closed and the discharge of material shifted at will from one side of the machine to the other, so that the material or product may be shiftably directed 90 out of the machine or so that the product of one or more sieves may be directed out of the machine at one side and the product of the remaining sieves of the set at the other side at will.

In Fig. 2 of the drawings I have reproduced substantially what is shown in Fig. 3 of the drawings of the Brantingham application above referred to, except that upon the lower six sieves I have shown my improved 95 shifting-gates applied so that said six sieves may be caused either to discharge in the

same direction as the others of the set, as those of the Brantingham do, or at will caused to discharge on the opposite sides, so that the entire product may either (as in 5 Brantingham's machine) flow into one receptacle or be divided and a part flow into one receptacle and a part into another receptacle, as may be desired. I may here remark that the number of receptacles in the bottom of 10 the machine is, as shown in Fig. 4 of the drawings, increased by one over the number used in a machine of similar arrangement and capacity by Brantingham; but otherwise I have shown no change in the structure of 15 the machine proper from the Brantingham construction. The arrangement in general is shown in Figs. 1 to 4, inclusive; but the details, which will now be described, are shown more clearly and on a larger scale in the remaining figures of the drawings. 20

Referring now especially to Fig. 5, it will be seen that the two gates 1 and 2 are mounted upon the rods 3 and 4, which rods are connected together by a bridge-bar 5 and 25 (through said bridge-bar) are actuated by means of a lever 6. In said Fig. 5 one position of the parts is shown by means of dotted lines and the other position by means of full lines, and it will be observed that in each 30 case one of the otherwise open sides of the sieve upon which the device is mounted is closed by the corresponding gate, while the other of said sides is open, its gate being positioned at a little distance away.

35 It being desirable that the parts should be assembled and disassembled easily, I have made them of a peculiar construction. On the ends of the rods 3 and 4 opposite from those ends to which the operating-lever is 40 connected I have placed small dovetail-shaped heads 7, and upon the face of the gate 1 I have placed corresponding members 8, having dovetailed grooves adapted to receive said dovetail heads. The gates 1 themselves, 45 as best shown in Figs. 12 and 15, have outwarded lips 1, which extend out over the heads 7 and stop said gates at the proper place vertically when they are placed upon the ends of the rods, as will be readily understood. By this means the gates 1 are rendered easily removable and replaceable.

50 The gates 2 are provided with combination devices 9, having both dovetailed grooves and perforated internally - screw - threaded hubs. Into these hubs the opposite ends of the rods 3 and 4 enter, so that the gates 2 are commonly securely attached to said rods. Short rods 10 and 11, which when the parts are assembled are, in effect, prolongations of the 55 rods 3 and 4, have upon their ends dovetailed heads 12, which enter the dovetailed grooves in the parts 9, while their other ends extend out and are connected to the bridge-bar 5 by

means of the clamping-nuts 13 14 or in any other suitable manner. Upon the operating 65 ends of the lever 6 is a saddle-piece 15, the arms of which extend down and embrace the bridge-bar 5 and operate the same. Centrally upon a bracket 16 is a pivot 17, which serves as a fulcrum for said lever. At or near a handle end of said lever 6 is a latch device 18, which engages at the limit of its movement with suitable engaging points on a bracket 19, so that the gates are held in one direction or another securely. 70

The faces of the frames of the sieves adjacent to the gates are provided with yielding strips 8 of wool, felt, or some such material as is usually used in milling appliances to make tight joints, so that no interstices 80 between the said sieves and said gates will be left, when the latter are closed, through which any material might pass in the wrong direction. This is illustrated more plainly in Fig. 6 than in any other figure. 85

The rods 3 and 4 themselves rest in bearings 20, which are secured upon the floor of the sieves themselves.

Having thus fully described my said invention, what I claim as new, and desire to secure 90 by Letters Patent, is—

1. The combination, in a sifting or separating machine, with a sieve having openings upon two sides, of connected shifting-gates, whereby one of the sides may be opened and 95 the other closed, and the open and closed sides reversed at will, substantially as set forth.

2. The combination, in a sifting or separating machine, with a sieve having openings upon opposite sides, of rods mounted in bearings in said sieve and extending through the same from side to side, gates upon the opposite ends of said rods, a bridge-bar connecting said rods, and means whereby the structure comprising the foregoing elements may be 105 shifted from one position to the other, whereby the openings may be alternately opened and closed, substantially as set forth.

3. The combination, in a sifting or separating machine, with a sieve having open discharging sides oppositely disposed, of gates for alternately opening and closing said open discharging sides, said gates extending through said sieves and resting in bearings 110 therein, a connecting-piece by which the two 115 are united, and a lever engaging with and adapted to operate said connecting-piece, substantially as set forth.

In witness whereof I have hereunto set my hand and seal, at Indianapolis, Indiana, this 120 30th day of October, A. D. 1899.

WALTER C. MARMON. [L. S.]
